Edward W. Hill,

ATTORNEY

UNITED STATES PATENT OFFICE.

EDWARD W. HILL, OF NEW YORK, N. Y.

LOOSE-LEAF-BOOK CONSTRUCTION.

1,008,597.

Specification of Letters Patent. Patented Nov. 14, 1911.

Application filed August 4, 1911. Serial No. 642,233.

To all whom it may concern:

Be it known that I, EDWARD W. HILL, a citizen of the United States, and resident of New York, in the county of Queens and 5 State of New York, have invented certain new and useful Improvements in Loose-Leaf-Book Construction, of which the following is a specification.

My invention relates particularly to a 10 note book or tablet construction for separate leaves or sheets of paper for instance, note paper.

The object is to provide a simple and inexpensive construction, the parts of which 15 can be readily and accurately assembled in manufacture and in which leaves or sheets of paper can be readily inserted and securely held and yet from which they may be readily removed. In my former application 20 #581,930 I have shown a somewhat similar construction.

It is the particular object of the invention claimed herein to simplify the former construction whereby the cost is reduced and 25 the parts may be more readily and accurately assembled in manufacture and operated.

In its preferred form the invention contemplates the use of a base or back cover 10 and either a top cover or cover bar or plate. The two parts carry telescopic posts near one edge for holding sheets of perforated paper. Adjacent each telescopic post is arranged a spring-like clasp, the parts of 15 which automatically interengage when the cover or cover plate is put on. The two upper clasp members are provided with projecting portions or finger pieces beneath which are locking shoulders and openings 20 to receive the other members of the clasps. The finger pieces are compressed when it is desired to separate the parts to remove any of the sheets. The parts are so arranged and constructed that the clasps can be readily 25 operated to release and separate the parts by holding the book with both hands, the cover being raised and the thumbs inserted beneath the cover, the forefingers pressing upon the finger pieces of the clasps 30 and the remaining fingers being underneath the book. When the finger pieces are pressed, the catches are released and the thumbs and forefingers may then be utilized to lift the cover.

Figure 1, is a perspective view showing

the operation of removing the cover. Fig. 2, is a perspective view of a construction having a top bar or cover plate instead of a complete cover, the parts being separated. Fig. 3, is a perspective view showing one of the clasps, the parts being connected. Fig. 4, is a perspective view showing the parts of the clasps and holders separated. Fig. 5, is an end view of the upper and lower portions with the parts of the clasps separated. Fig. 6, is a fragmentary detail sectional view showing one of the pairs of holding posts and clasps with the leaves. Fig. 7, is a plan view showing the method of alining one of the clasp parts with a post and supporting bar. Fig. 8, is a perspective view of the parts of a clasp separated. Fig. 9, is a rear view showing the parts of the clasp connected.

In the drawing 1 indicates the base or 75 back cover, 2 the top cover and 3 the perforated sheets or leaves constituting the filling.

4 and 5 indicate the clasps for connecting the parts together.

6 and 7 are the bottom and top bars 80 respectively which constitute the supporting plates for the clasping and holding means.

8 and 9 are the telescoping posts secured to the bars 6 and 7. Preferably there are two pairs of these posts for holding the 85 paper. These posts preferably have heads 10 and 11 respectively which prevent the posts from pulling through the bars.

12 and 13 are the arms of a clasp. A clasp is provided adjacent each post. Preferably these clasps are formed of sheet metal such for instance as spring brass so that they will be durable and elastic. They may of course be nickelized or otherwise plated. The two arms 12 and 13, when the parts are 95 together, overlap each other as shown in Figs. 1, 3, 6 and 9. The arm 12 has a rearwardly projecting shoulder 14 and the arm 13 has a shoulder 15. The tip of the arm 12 is preferably inclined outwardly as 100 shown in Fig. 5 and the shoulder 14 is formed by indenting the metal and forming an incline 17. The shoulder 15 is formed by cutting the metal and forcing outwardly a portion 19 which leaves an opening beneath a wider than the arm 12, the edge 18 being inclined downwardly somewhat as shown in Fig. 5.

The parts are adapted to be connected by inserting the post 9 into the tubular post 8 110

and then pressing down the top bar 7. The tip 16 passes by through the opening beneath the projection 19 and the incline 17 slides over the incline 18 until the shoulders 14 and 15 are enabled to snap into engagement with each other. The parts are then locked securely together.

It will be noted that the length of the posts 8 and 9 is such relatively to the clasp 10 arms 12 and 13 that the posts are partially telescoped before the clasp members begin to overlap.

The clasp members are preferably formed of sheet metal as mentioned and the arm 12 15 has a base plate portion 20 bent at right angles and which fits over the edge of the bar 6. This plate portion also has lugs 21, 21 adapted to be positioned by the head 10 of the post 8 so that in assembling the parts 20 in manufacture the clasp member with its spring arm 12 will be in the proper position relative to the post 8. When the plate 20 is in position on the bar 8, the parts are connected in a suitable manner as for instance 25 by means of a rivet 22. In a similar manner the upper clasp member has a plate portion 23 with lugs 24, 24 positioned by the head 11 of the post 9 and is secured to the bar 7 by means of a rivet 25.

30 It will be noted that when the parts of the clasp are interengaged they are in the position of Figs. 6 and 9. By pressing inwardly on the projecting portion 19 the shoulder 15 may be disengaged from the 35 shoulder 14. To permit this a space 26 is left between the ends of the leaves 3 and the parts of the clasp. The part 19 therefor constitutes an operating button or finger piece. When two clasps are employed as 40 shown herein, which is the preferred form, the clasps may be readily released by engagement of the forefingers as shown in Fig. 1 and the cover removed by the use of the thumbs and forefingers. In making the 45 finished book, strips of cardboard 27 and 28 may be used underlying and overlying respectively the bars 6 and 7 and any suitable form of fabric such as 29 and 30 may be used to embellish or otherwise finish the book 50 and its fittings.

The tip of the arm 12 is preferably considerably narrower than the opening beneath the finger piece or operating button 19 so as to allow for some variations in construction and assembling. By this construction 55 where the operating button overlies the engaging shoulders both of the clasps are the same, that is, there are no rights and lefts as would be the case if the operating button 60 were located on one side or the other of the engaging shoulders. It is therefore possible to use the clasps interchangeably at the right or left of a book. Obviously these clasps may be made in different sizes. It will be 65 noted however, that this binder is primarily

inextensible and only calculated to be used with a given thickness of paper. Obviously however, the exact number of leaves employed is unimportant.

What I claim is:—

1. In a loose leaf book construction, the combination of a base, two tubular posts carried thereby adjacent one edge, loose perforated leaves thereon, a cover, two posts carried thereby for telescoping with the tubular posts, a clasp member adjacent each post, each clasp member consisting of an elastic arm of sheet metal, opposite clasp members overlapping and provided with automatically interengaging abrupt shoulders, the members whose shoulders fit behind the other shoulders being provided with projecting portions constituting buttons overlying the shoulders to receive the pressure of the fingers to disengage the shoulders while the base and cover are held so as to permit immediately subsequent separation of the parts substantially as shown and described.

2. In a loose leaf book construction, supporting plates, telescoping posts carried by said plates, clasp members arranged in pairs and having base plate portions secured to the supporting plates and with lugs positioned by said posts, said clasp members also having spring arm portions bent at substantially right angles to the base plate portions and provided with automatically interengaging shoulders, one of the spring arm portions of each pair being provided with means for digital engagement for releasing the shoulders.

3. In a loose leaf book construction, supporting plates having perforations, headed telescopic posts carried by said plates and having their heads outside of said plates and their shanks extending through said perforations, and a pair of bent spring clasp members each having a base plate with lugs positioned by the heads of the posts, rivets for securing the base plates to the supporting plates adjacent the posts.

4. In a loose leaf book construction, a clasp comprising a spring arm having a backwardly directed shoulder and an outwardly projecting finger piece with an opening between the finger piece and the shoulder and a second arm adapted to slide into said opening and having a shoulder to automatically engage the first mentioned shoulder when the arms are brought into engagement.

5. In a loose leaf book construction, telescoping leaf supporting posts and elastic sheet metal clasp arms adapted to overlap each other adjacent the posts, one of said arms having a finger engaging portion with an opening beneath it and a shoulder behind it, the other arm being adapted to enter the opening and having a shoulder for au-

tomatically engaging the first mentioned shoulder when the arm has entered the opening and the posts are telescoped.

6. In a loose leaf book construction, telescoping leaf supporting posts and elastic sheet metal clasp arms adapted to overlap each other adjacent the posts, one of said arms having a finger engaging portion with an opening beneath it and a shoulder behind it, the other arm being adapted to enter the opening and having a shoulder for automatically

engaging the first mentioned shoulder when the arm has entered the opening and the posts are telescoped, the relative length of the posts and arms being such that the 15 posts begin to telescope before the arms come into engagement.

EDWARD W. HILL.
